UNITED STATES PATENT OFFICE.

FRANZ O. LIMING, OF CHICAGO, ILLINOIS, ASSIGNOR OF ONE-HALF TO JOHN M. LIMING, OF FAIRFIELD, IOWA.

DOOR-CONTROLLING APPARATUS.

1,352,980.

Specification of Letters Patent. Patented Sept. 14, 1920.

Application filed March 27, 1919. Serial No. 285,587.

To all whom it may concern:

Be it known that I, FRANZ O. LIMING, a citizen of the United States, residing at Chicago, in the county of Cook and State of Illinois, have invented certain new and useful Improvements in Door-Controlling Apparatus, of which the following is a specification.

One of the objects of the invention is to provide an organized mechanism for automatically closing a hinged door, when the latter is operated within a given limit of its movement, and which will retain the door in open position by moving the door beyond said limit of movement, and so arranged that still further movement of the door, in the same direction, will disengage the holding means to release the door, whereupon it will automatically operate to close the door. For example: When the door is opened to an extent, say, less than 90 degrees from its closed position, the mechanism will automatically close the door, as soon as the door is manually released, but if the door be opened to an extent greater than 90 degrees, and manually released, the mechanism will retain the door in its open position. Thereafter, to close the door it is only necessary to further move it, in the same direction, to a slight extent, whereby to disengage the door-holding mechanism, whereupon the door will then be automatically closed and will continue to be automatically closed each time it is opened until the door is once more opened beyond said limit of movement.

The organized apparatus disclosed herein comprises a door-holding mechanism, such as disclosed in my Patent No. 1,291,033 granted January 14, 1919, and an improved combinatively related door-closing mechanism hereinafter specifically pointed out.

Other and further objects of my invention will become readily apparent, to persons skilled in the art, from a consideration of the following description when taken in conjunction with the drawings, wherein:—

Figure 1 is an elevation of the upper part of a hinged door showing the door-controlling mechanism in place.

Fig. 2 is a transverse section taken on line 2—2 of Fig. 1.

Fig. 3 is a vertical central section of the door check; and

Fig. 4 is an elevation of the door holding

means as specifically pointed out and claimed in the aforesaid patent.

In all the views the same reference characters are employed to indicate similar parts.

In the illustrated embodiment of the invention, 5 is a door hinged, as at 6, to a jamb 7. Secured to the door at a suitable location, and near its top end, is a door holding catch 8 and fixed to the door, parallel with the catch mechanism, is the catch rod 9 spaced away from the door and secured at one end by a bracket 10 and at the other end by a bracket 11. The bolt 12 of the latch is adapted to have limited movement on the rod 9. Secured to the upper frame member of the door jamb, is a bracket 13, in which is pivoted an arm 14. The outer free end of the arm is bifurcated, there being a short member 15 and a relatively longer member 16. The latter member is pivoted to a lug 17 that freely slides upon the latch rod 9. Pivoted to the bracket 18, which is fixed to the door 5, is a pneumatic door-check cylinder 19, provided with a piston 20. A piston rod 21 is secured to the piston and passes through an end 22, of the cylinder, into a relatively small cylinder 23, that is pivoted, as at 24, to the shorter arm 15 of the major arm 14. On the outer end of the piston rod 21, is a head 25, that prevents the outer end of the rod 21 from leaving the cylinder 23, the latter being contracted at its outer end by an inturned part of the cylinder wall for that purpose. The smaller cylinder 23 permits some lost motion movement between the piston, and the arm member 14, when the door is opened and closed, so that the initial movement of the door, in either direction, is not cushioned or resisted by the pneumatic cylinder and the axially moving piston therein. The rear head 22 of the cylinder is provided with a vent 26 so that when the piston moves rearwardly, the air passes out more or less freely from the cylinder and there is very little cushioning effect.

The head 27 at the front end of the cylinder is provided with a regulable vent effected by the screw 28. The screw is tapered so as to regulate the area or size of the vent and this has the effect of retarding the movement of the piston, within the cylinder, to a greater or less extent, during door closing operation.

When the door is being opened, the lug 17, connected to the arm 16, moves along the

latch rod 9 until it encounters the slideable bolt 12, of the catch 8, and after it has moved the bolt 12 to a prescribed degree along the rod, the mechanism is so operated that the 5 latch 30 falls down within the return path of the lug 17, and thereby the door is held in open position. This does not occur, however, until after the door has been moved beyond the distance, that admits of engagement 10 of lug 17 and bolt 12, to which it may be moved without being affected by the catch.

The use and operation of the catch mechanism is shown and fully described in the 15 patent to which reference has heretofore been made.

When the lug 17 has been moved beyond the position shown in Fig. 4, the bolt 12 operates to raise the latch 30 out of the path 20 of the lug 17, whereupon the door will be freely moved, by the two springs 32 and 33 that are coiled about the axis of the arm 14 to closed position. A spring 34 may be placed around the rod 9 to assist the spring 25 35 within the latch mechanism 8.

Fig. 2 shows in full lines and in dotted lines the positions of the door and mechanism, when the door is closed and when it is partly open, respectively.

30 While I have herein shown a single embodiment of my invention for the purpose of clear disclosure it will be manifest to persons skilled in the art that considerable changes may be made in the general arrangement and configuration of the parts 35 within the scope of the appended claims.

Having described my invention, what I claim is:

1. A door controlling mechanism having 40 in combinative relation, means to automatically close the door within a prescribed

range of door movement; means to hold the door open, when moved beyond said range of movement, and to release the door when it is further moved in the same direction, 45 and a lost motion connection between the door closing means and the door.

2. A door controlling mechanism having in combinative relation, means to automatically close the door within a prescribed 50 range of door movement, comprising a pneumatic cylinder having one end pivoted to the door; a piston therein; a spring-urged, bifurcated arm, having one member connected to said piston; a door-catch having a 55 bolt projecting therefrom, mounted on the door; a guide rod for said bolt, mounted on the door parallel with the catch, and a lug, slideable on said rod and pivotally connected to the other member of said arm, whereby 60 to co-operatively connect the door-holding means and the door-closing means for the purpose described.

3. A door controlling means having in combinative relation, a cylinder pivoted to 65 the door; a piston therein; a spring-urged arm pivoted to the door jamb and bifurcated at its free end by a short and a long member, said short member connected to said piston; a lost-motion device in said connection; a rod, substantially parallel with the upper end of the door and secured thereto; a lug, movable along said rod, by movement of said door, and pivotally connected to the longer member of said arm and a 70 door-holding mechanism, operable by movement of said lug, along said rod, when the door has been opened to a predetermined degree.

In testimony whereof I hereunto sub- 80 scribed my name.

FRANZ O. LIMING.
